UNITED STATES PATENT OFFICE.

ROBERT J. DELEHANTY, OF CLEVELAND, OHIO, ASSIGNOR TO THE AMERICAN MULTIGRAPH COMPANY, OF CLEVELAND, OHIO, A CORPORATION OF OHIO.

PRINTING DEVICE.

Application filed October 16, 1926. Serial No. 141,972.

A large number of multigraph or office printing machines are in use throughout the country. Such machine has a rotary drum with parallel overhanging rails along its 5 surface formed to carry between them rows of grooved individual type. Patent No. 1,557,754 issued October 20, 1925, to my assignee, The American Multigraph Company, as assignee of Clifton Chisholm, 10 shows an embossed printing strip, having a single row of characters and having inwardly flanged edges, as well as a keyboard machine for the efficient production of such strips. 15 Now, I have devised a very simple expedient by which existing multigraph machines may be adapted to carry such line strips in place of the individual type heretofore used. Such device constitutes the 20 subject matter of this invention.

My invention comprises straight bars having grooves in their opposite sides, whereby they may be mounted between the overhanging heads of parallel rails on the multigraph drum, and having on their tops dove tailed or overhanging ribs onto which the embossed strips may be slid. The head of the bar together with the embossed strip mounted thereon has preferably the same 25 height as the head of the type on the multigraph, wherefore my printing device may be used in conjunction with type in the same form. My invention is illustrated in the drawings hereof and hereinafter more fully 30 explained.

In the drawings Fig. 1 is a fragmentary end view of a multigraph drum equipped with some of my printing members and also with regular multigraph type; Fig. 2 is a 40 fragmentary sectional perspective of a portion of such drum so equipped; Fig. 3 is a vertical section of a flat railed support equipped with one of my printing members and with individual type; Fig. 4 is a perspective of one of my bars, together with 45 a portion of an embossed strip mounted thereon.

In Figs. 1 and 2, A indicates a multigraph drum or segment. Into the surface of this 50 are set parallel rails B of I-shape in cross section a short distance apart, each rail having a base portion b occupying a corresponding groove in the support and an overhanging head b^1 separated by side grooves b^2 . The support is ordinarily slightly

peened over above the rail base to lock them in place. After the drum is made its outer surface is preferably ground to a true cylinder.

The construction in Fig. 3 is similar except that in place of a segment of the drum, I have shown a flat base A¹, and the tops of the rails are flat and parallel with the bottom of the base. 60

In Figs. 1, 2 and 3, C indicates the usual multigraph type having a body provided with grooves on opposite sides, whereby there is left a head which may be above and rest on the rails, while the grooved sides receive the overhanging of the rails, and a 65 base portion stands beneath the rail heads. The body carries on its face suitable printing characters c. 70

Now, to enable the embossed strips to be used on such railed drums or supports, as a 75 substitute for the type, I provide the bars shown at D in Fig. 4. Each bar is a metal member having grooves d on its opposite sides, thus leaving a head member d¹ and a base member d². Such bars are thus adapted to be inserted endwise into the channels between the ordinary rails B. Each bar has along its upper surface a rib d³ with outwardly inclined edges, in other words, such 80 rib constitutes a dove tail. 85

The embossed printing strips are designated E. Each consists of a thin metal member having upwardly embossed characters e and having inwardly flanged edges e¹. The dove tail d³ is of such size that the embossed strip may slide over it somewhat snugly and remain in place thereon. The thickness of the head flange e¹ of my bar, together with the dove tail is such that when the embossed strip is mounted thereon its printing character e may be in the same cylindrical surface, or in the same plane, as the character c of the type. Thus both type and my printing members may be used together in the 90 same form. 95

It will be noticed that the ribs d³ are considerably narrower than the head portion d¹, with the result that the embossed strips E may be mounted on such dove tailed ribs without extending laterally further than the heads d¹. In fact, I have shown the strips and ribs narrow enough so that the strips are out of contact with each other or with adjacent type, which provides for greater 100 freedom of mounting as well as enabling an 105 110

underscoring rule to be mounted alongside of any strip.

It will be seen that by the means described embossed line strips may be readily mounted 5 on existing railed drums or supports, thus enabling the latter to utilize embossed strips for complete lines whenever desired. The invention is very useful in increasing the adaptability of existing multigraph machines. By this means the user of such machine may very quickly convert it from a type carrying machine into a machine suitable for carrying embossed printing strips. In circular letter work, for instance, 10 the same line or paragraph is frequently repeated on successive jobs, and by using embossed strips with my bars for such repeated lines and the changeable type for the changed portion, the user may greatly reduce the time required for setting up a form.

I claim:

1. The combination with a support having parallel rails with overhanging edges, of a bar adapted to be mounted between adjacent rails, and held thereby, an embossed printing strip, and means for holding it on the top of the bar.

2. The combination with a support having parallel rails with overhanging edges, of a bar grooved on its opposite sides and adapted to be slidably mounted between adjacent rails, an embossed printing strip, and means for holding it on the top of the bar.

3. The combination of a support having parallel rails with overhanging edges, grooved bars adapted to be slid into place between adjacent rails, each bar having on its top an overhanging head, and an embossed printing strip having inwardly flanged edges, said strip being slid into place on the head of the bar.

4. The combination with a base carrying parallel rails with overhanging edges, a bar slid endwise into place between adjacent rails, said bar having on its top a dove

tailed rib, and an embossed printing strip mounted on said rib.

5. The combination with a base carrying parallel rails with overhanging heads, a grooved bar adapted to be mounted between said heads and having a head portion resting on the heads of the rails and a base portion lying in the grooves of the rails beneath their heads, said bar having along its top a dove tailed rib, and an embossed printing strip resting on said rib and having inwardly projecting edge flanges engaging at the sides of the dove tailed rib beneath the same.

6. The combination with a supporting member having parallel rails with overhanging edges, a row of grooved individual type mounted between a pair of adjacent rails, a grooved bar mounted between a pair of adjacent rails, said bar having a projection on its top, and an embossed printing strip mounted on said projection, the characters of the embossed strip and of the individual type standing the same height-to-paper.

7. As a new article of manufacture, a bar adapted to enable a railed support to carry embossed strips, said bar being a straight member having grooves in its opposite sides and having an upwardly extending overhanging projection at its top.

8. As a new article of manufacture, a single integral bar for enabling a railed type holding member to carry alternatively embossed printing strips, individual type and said bar having grooves in its opposite sides leaving a base portion below the grooves and a head portion above, said head portion having a centrally located dove-tailed rib narrower than the rest of the head extending along the top.

In testimony whereof, I hereunto affix my signature.

ROBERT J. DELEHANTY.
